UNITED STATES PATENT OFFICE.

ISABELLE REDLES, (NOW BY MARRIAGE ISABELLE R. SHILL,) OF SWARTHMORE,
PENNSYLVANIA.

PIN-FASTENER.

No. 884,611.

Specification of Letters Patent.

Patented April 14, 1908.

Application filed May 16, 1904. Serial No. 208,230.

To all whom it may concern:

Be it known that I, ISABELLE REDLES, (now by marriage ISABELLE R. SHILL,) a citizen of the United States, and a resident 5 of Swarthmore, Delaware county, Pennsylvania, have invented certain Improvements in Pin-Fasteners, of which the following is a specification.

The object of my invention is to provide 10 an improved form of pin fastener whereby a bow or other ornament may be readily and securely attached to a dress, hat or other article of wearing apparel, and my invention consists of a duplex pin fastener, comprising 15 a pair of safety pins secured together, back to back, in line with or at a right or other angle with respect to each other, so that one may be caused to engage with a bow or other ornament, and the other with a dress, hat or 20 other article of wearing apparel to which said bow or other ornament is to be affixed; the convenient and secure retention of said bow or ornament in any position desired being thereby effected.

25 The improved pin fastener forming the subject of my invention is fully shown in the accompanying drawings, in which:

Figures 1 and 2, illustrate respectively different forms of a duplex pin fastener embodying my invention.

Each of the pins forming the duplex fastener shown in the drawing, consists of a substantially broad, flat bar 1, terminating at one end in a pin 2, which extends rearwardly 35 substantially parallel with said bar 1; the opposite end 3 of the latter being bent to form a shield or guard which acts as a retainer for the point of the pin.

The two pins may either occupy a position 40 parallel with each other, as shown in Fig. 1, or they may be disposed at a right or other angle with respect to each other, as shown in Fig. 2, of the drawings, such latter disposition of the pins permitting the ready adjustment 45 of a bow or other ornament to a dress, where the bow is not intended to lie parallel with the portion to which it is attached and is particularly desirable for use at the back of the neck; one pin being disposed in one position 50 as most convenient to secure the collar or back of the waist, while the other pin affords

proper support and attachment for a bow. In either instance, the pin engaging said bow or ornament serves as a stiffener to retain the same in its upstanding or other position. 55

The backs of the pins may be secured together by soldering or brazing, or, as shown in the drawings, by riveting. A single rivet is shown, and to prevent the pins from twisting out of their original position with respect 60 to each other, the bar 1 of one of the pins is shouldered by pressing up the projection 5, as shown in Fig. 1, or recessed at 6 to provide shoulders, as shown in Fig. 2.

While I prefer to employ the ordinary 65 form of safety pin, without hinge, in carrying out my invention, I wish the term "safety pin" to be construed broadly enough to cover any pin whose point engages with a shield or retainer, whether such pin is hinged, 70 as shown at 7 in Fig. 1, or is integral with the back, as shown in Fig. 2.

I claim:

1. In a duplex pin fastener, the combination of a pair of independent safety pins each 75 having a broad flat back, and means passing through said backs for securing them together with their broadest area in contact, the back of one pin being shouldered for engagement with the back of the other pin. 80

2. In a duplex pin fastener, the combination of a pair of independent safety pins each having a broad flat back, means passing through said backs for securing them together with their broadest area in contact, 85 and means carried by one pin and independent of the securing means for retaining said pins in planes transverse to each other, said retaining means serving also to prevent the movement of either pin with respect to the 90 other.

3. In a duplex pin fastener, the combination of a pair of independent safety pins each having a substantially broad, flat back, and means for securing said backs together with 95 their broadest area in contact, the back of one pin being recessed to provide shoulders for engagement with the back of the other pin to prevent turning movement of one pin with respect to the other. 100

4. In a duplex pin fastener, the combination of a pair of independent safety pins each

having a substantially broad, flat back, and
means for securing said backs together with
their broadest area in contact, the back of
one pin being shouldered for engagement with
5 the back of the other pin, said pins being dis-
posed in planes transverse to one another.

In testimony whereof, I have signed my

name to this specification, in the presence of
two subscribing witnesses.

ISABELLE REDLES.
